UNITED STATES PATENT OFFICE.

LYNDON WHITE MANHEIM, OF CAMDEN, SOUTH CAROLINA.

FREIGHT-CAR DOOR.

1,380,229.

Specification of Letters Patent. Patented May 31, 1921.

Application filed August 24, 1920. Serial No. 405,596.

To all whom it may concern:

Be it known that I, LYNDON W. MANHEIM, a citizen of the United States, and a resident of Camden, in the county of ⁵Kershaw and State of South Carolina, have invented a new and Improved Freight-Car Door, of which the following is a full, clear, and exact description.

This invention relates to improvements in ¹⁰ freight cars and doors therefor, an object of the invention being to provide a door construction for cars of this type which will greatly facilitate the loading and unloading of the car.

¹⁵ A further object is to provide side and end door constructions which will obviate the necessity of using draw boards to load or unload freight cars, as the doors themselves form inclined gang planks which permit ingress or egress from the cars.

²⁰ Another object is to provide freight car doors which may be readily opened and closed. The sliding doors now in general use are very difficult to operate, especially ²⁵ when the cars are loaded and jars and vibrations incident to moving of the car have caused the freight to jam against the sliding doors.

³⁰ Still another object is to provide end and side doors hinged at their lower edge and adapted to swing outwardly and to provide improved means for controlling the position of the doors so that they may be used either for platforms or runways.

³⁵ With these and other objects in view, the invention consists in certain novel features and construction and combinations and arrangement of parts as will be more fully hereafter described and pointed out in the ⁴⁰ claims.

In the accompanying drawings,

Figure 1 is a perspective view of the body of a freight car with my improved doors and operating mechanism attached.

⁴⁵ Fig. 2 is a view in end elevation of the freight car body.

Referring in detail to the drawings, 1 represents the body of a box car of the usual type. The side doors 2 of the car are ⁵⁰ probably made in three sections. The lower half of the door comprises a section 3 hinged at its lower edge, as shown at 4, and adapted to swing outwardly and downwardly. The upper half of the door comprises a pair ⁵⁵ of sections 5, 5, hinged at their side edges and adapted to swing outwardly.

The car is also provided with one or more end doors 6 supported at their lower edges by hinges 6' and adapted to swing outwardly and downwardly. The doors 6 ⁶⁰ themselves form the end walls of the car, and since these doors are necessarily heavy, I provide an improved means for operating the same. A description of one of the operating mechanisms will suffice for both, ⁶⁵ since both are identical. A shaft 7 is mounted transversely under the end of the car in bearing brackets 8. Rotary drums 9 are mounted on each end of the shaft 7 and one of the drums is fixed to turn with a ⁷⁰ gear wheel 10. At each side of the car adjacent to the upper corners of the end doors, pulleys 11 are supported in angle brackets ⁷⁵ 12. Flexible devices 13 secured adjacent the upper edges of the door as shown at 14 ⁸⁰ are passed over the pulleys 11 and secured around the drums 9. A pinion 15 mounted on a short shaft 16 meshes with the gear wheel 10. Any suitable crank handle 17 may be used to turn the shaft. A pivoted locking dog 18 is employed to engage the pinion ⁸⁵ 15 and hold the door 16 in any desired position of adjustment. The door may be let all the way down to the ground, as shown in Fig. 1, to form an inclined gangway for ⁹⁰ loading or unloading the car, or it may be lowered or located in a horizontal position to form a platform; the position of the door, of course, depending upon the nature of the goods to be handled and the unloading facilities.

The lower section of the side doors may be operated in any suitable manner and any type of locking device, such as that illustrated at 19, may be employed to fasten the ⁹⁵ upper sections of the side doors together.

While I have illustrated one of the preferred embodiments of my invention, it is obvious that various slight changes and illustrations might be made in the general ¹⁰⁰ form of the parts described without departing from my invention, and hence I do not limit myself to the precise details set forth, but consider myself at liberty to make such slight changes and illustrations as fairly ¹⁰⁵ fall within the spirit and scope of the appended claims.

I claim:

1. In a freight car, a door forming the end wall of the freight car and hinged at ¹¹⁰ its lower edge to the floor of the car, a shaft mounted transversely of the car and below

the same, winding drums on the ends of the shaft fixed to turn therewith, outwardly presented angle brackets affixed to opposite sides of the car adjacent the upper end of the door, laterally extending studs on the upper end of the door, pulleys mounted in the angle brackets, flexible devices having their intermediate portions located over the pulleys and their ends operatively connected to the studs and the winding drums, and means for driving the shaft.

2. In a freight car, a door forming the end wall of the freight car and hinged at its lower edge to the floor of the car, a shaft mounted transversely of the car and below the same, winding drums on the ends of the

shaft fixed to turn therewith, outwardly presented angle brackets affixed to opposite sides of the car adjacent the upper end of the door, laterally extending studs on the upper end of the door, pulleys mounted in the angle brackets, flexible devices having their intermediate portions located over the pulleys and their ends operatively connected to the studs and the winding drums, a gear wheel fixed to turn with one of the winding drums, a short shaft projecting laterally from the side of the car, a pinion on the short shaft meshing with the gear wheel, and means for operating the last mentioned shaft.

LYNDON WHITE MANHEIM.
